Glass Manufacturing Co., Inc., New York, N.Y., a corporation

Application November 4, 1958, Serial No. 53,268

Term of patent 14 years

(Cl. D58—8)

Fig. 1 is a side elevational view of a bottle embodying my design; and

Fig. 2 is a cross-sectional view thereof on the line 2—2 of Fig. 1.

The bottle is circular in cross-section throughout. The side not shown is substantially the same as the side shown.

Fig. 1 is lined to indicate contrasting colored areas.

I claim:
The ornamental design for a bottle, as shown and described.
